DESIGN FOR A TABLE

Grover C. Rhodes, Culver City, Calif.

Application August 14, 1945, Serial No. 121,432

Term of patent 14 years

(Cl. D33—14)

To all whom it may concern:

Be it known that I, Grover Cleveland Rhodes, a citizen of the United States, residing at Culver City, in the county of Los Angeles and State of California, have invented a new, original, and ornamental Design for a Table, of which the following is a specification, reference being had to the accompanying drawing, forming part thereof.

The characteristic features of my design reside in the portions shown by means of full lines in the drawing.

I claim:

The ornamental design for a table, as shown and described.

GROVER C. RHODES.
